ORNAMENTAL BOX

Keaton G. Nichols, Butte, Mont., assignor of
one-half to William Kenneth Line, Butte,
Mont.

Application April 21, 1938, Serial No. 203,456

2 Claims. (Cl. 229—8)

The present invention relates to cardboard boxes of a type within which articles of merchandise are intended to be sold, the invention having for its primary object to provide 5 a box of this character which includes a bottom portion and a lid or cover portion, preferably adapted for telescoping engagement and providing both the bottom and top portions of the box with an inner permanently attached ornamental cover and placing an outer or service cover over the ornamental cover and providing means for conveniently removing the outer or service cover when desired, in order that the ornamental cover may be exposed to view.

10 A further object is to provide a merchandising box of this character in which the outer removable cover may be made of material commonly used in stock boxes and adapted to contain printed matter advertising the contents of 20 the box or the like, and providing means for removably securing said outer or service cover to the box without causing a mutilation of the inner or ornamental cover upon the removal of said service cover.

15 An additional object is to provide a device of this character of simple and practical construction, which is neat and attractive in appearance, relatively inexpensive to manufacture and otherwise well adapted for the purposes for which the 25 same was intended.

20 Other objects and advantages reside in the details of construction and operation as more fully hereinafter described and claimed, reference being had to the accompanying drawings forming 30 part hereof, wherein like numerals refer to like parts throughout, and in which

Figure 1 is a perspective view of the lid of a box showing the outer cover in position thereon.

25 Figure 2 is a similar view of the bottom of a 35 box.

Figure 3 is a sectional view taken substantially on a line 3—3 of Figure 2, and

40 Figure 4 is a group perspective view of the top of the box and the blanks forming the inner 45 and outer covers therefor.

45 Referring now to the drawings in detail, wherein for the purpose of illustration I have disclosed a preferred embodiment of the invention, the numerals 5 and 6 designate the top and bottom sections respectively of a telescoping box, each being of substantially rectangular formation and the top including side walls 7, end walls 8 and a top wall 9 whereas the bottom 6 includes side walls 10, end walls 11 and a bottom wall 12.

50 The top and bottom portions of the box are

preferably constructed of cardboard and secured to the outer surfaces of the top and bottom sections is an inner cover 13, which may be formed of paper or other suitable material and preferably adapted to contain any desired ornamentation printed or otherwise placed thereon to add to the attractiveness thereof. The inner cover 13 is preferably secured to the outer surfaces of the box by gluing or the like.

5 The inner cover 13 includes a central portion 14, side flaps 15 and end flaps 16 adapted to be folded respectively against the side and end walls of the box. The flaps 15 and 16 also include pointed tabs 17 adapted to be folded against an adjacent wall of the box as shown 15 by the dotted lines in Figures 1 and 3 of the drawings.

10 Placed over the inner cover 13 is an outer cover 18 which likewise includes a central portion 19, side flaps 20 and end flaps 21, said flaps 20 also being provided with tabs 22 and arranged for positioning over the box in the same manner as the inner cover 13.

15 Arranged along the outer edges of the flaps 20 and 21 are longitudinal extensions 23 and 24 25 respectively connected to their respective flaps by lines of perforations 25. The extensions 23 and 24 of the respective flaps are adapted to be folded inwardly against the inner surfaces of the side and end walls of the box and are secured 30 in position thereto by glue or the like.

20 The outer cover 18 is adapted to contain printed matter advertising the contents of the box or other suitable advertising matter, and when desired, as for instance, when a customer has purchased the contents of the box, the outer cover 18 may be removed by tearing the same along the perforated edges 25 thereby exposing the inner or ornamental cover, thereby removing the advertising matter and exposing the attractive ornamental cover, thereby making the box 40 suitable as a gift box.

25 It is believed the details of construction and manner of use of the invention will be readily understood from the foregoing without further 45 detailed explanation.

Having thus described the invention, what I claim is—

30 1. A box of the class described formed of a plurality of walls, said box having an open portion, an inner flexible covering secured to the outer surfaces of the box, an outer flexible cover for the exposed surfaces of the inner cover and free therefrom and means for securing the marginal edges of said outer cover to the inner sur- 35 40 45 50 55

faces of the box, said secured edges of the outer cover being separable from the remaining portion of the cover.

2. A box of the class described formed of a plurality of walls, said box having an open portion, an inner ornamental cover secured to the outer surfaces of said walls, an outer service cover positioned over the outer surface of said inner

cover and extensions on the edges of said outer cover adapted to be folded inwardly and secured to the inner surfaces of said walls adjacent the open portion and lines of separation connecting said extensions to said outer cover, 5 said outer cover being adapted for removal along said lines of separation.

KEATON G. NICHOLS.
